Frederick Wilford

UNITED STATES PATENT OFFICE.

FREDERICK WILFORD, OF EAGLE, WISCONSIN.

IMPROVEMENT IN APPARATUS FOR WALLING CISTERNS.

Specification forming part of Letters Patent No. 159,239, dated January 26, 1875; application filed December 7, 1874.

To all whom it may concern:

Be it known that I, FREDERICK WILFORD, of the town of Eagle, county of Waukesha and State of Wisconsin, have invented a new and useful Improvement in the Apparatus for Walling Wells, Cisterns, and Mine-Shafts with Grout; and I do declare that the following is a full and exact description thereof, reference being had to the accompanying drawings and to the letters of reference marked thereon, of which—

Figure 1 is a perspective elevation, with movable or swing stave and platform, hereafter described, in place. Fig. 2 is a perspective elevation, but with the movable or swing stave swung inward, and the platform removed from the top of the cylinder. Fig. 3 is a plane longitudinal view of the cylinder, showing ribs, extension-braces, connecting-rod, hinges, and bail-loops.

The nature of my invention consists in constructing a cylinder with spring-steel ribs, so that it may be caused to collapse evenly and equally to such an extent that it may easily be detached and drawn out of the grout wall formed around it.

To enable others skilled in the art to make and use my invention, I will proceed to describe its construction and operation.

I construct my apparatus in the form of a hollow cylinder, of the length and diameter desired. For walling wells, about six feet long, and from thirty to forty inches in diameter, I first make two circular spring-steel ribs of uniform section, as shown at *a a*, Figs. 2 and 3, of sufficient strength to sustain the pressure when the grout is being packed around the cylinder, as hereinafter described. To the periphery of these spring-steel ribs, which are to be placed at appropriate distances apart, I attach segmental staves, by means of screws or bolts, until the cylinder is formed, except a space of the width of the movable or swing stave hereafter described. These staves I make about three-fourths of an inch thick and three inches wide, dovetailing or matching them together. The movable or swing staves I make about twelve inches wide, of the same thickness and shape as the main part of the cylinder, to which it is hung by hinges, of which the spring-steel ribs form a part, and so ar-

ranged as to allow the movable or swing stave to swing inward, as seen at *c*, Fig. 2. The movable or swing stave, with the one against which it shuts, should have their edges beveled sufficiently to allow a free swing of the movable stave; but the bevel should not be so great as to allow the corresponding edges to slide upon each other when the cylinder is subjected to external pressure. I use two extension-braces or stretchers inside of each cylinder, as shown at *d d*, Fig. 3. Each extension-brace or stretcher is made with a joint in the middle, similar to the shouldered-joint in a carpenter's pocket-rule. The object of this joint is, that the extension-brace may be sprung upward by a pull on the ring above the joint, but not downward below a slight depression from a straight line, from which latter position they will not spring upward by pressure at the ends. Each extension-brace or stretcher should terminate at both ends with a hook, to work in an eye fastened to the inside of the cylinder, forming a variable joint. The two extension-braces or stretchers are worked and operated together by means of a connecting-rod, shown at *e*, Fig. 3. One end of each brace or stretcher is to be attached to the inside of the movable or swing stave, near its opening edge, and near the top and bottom thereof, and the other end at a point on the inside of the cylinder directly opposite. The connecting-rod *e*, Fig. 3, terminates at top above the upper brace with a ring, *f*, by which a pull may be made on the center of the stretchers, bringing them upward, and the movable stave inward. Two inches below the top on the inside of each cylinder, and at a point at right angles to the point where the stretchers are attached, I securely fasten two bail-loops. These are seen at *g g*, Fig. 3. When suspending, lowering, or raising the cylinder, a bail is hooked into these bail-loops, and to this bail a rope is attached, which passes to a windlass which controls the operation of lowering or raising the cylinder. I next construct a platform of the same diameter as the cylinder when fully extended by the extension-braces, the movable stave in place. This platform should be made of one-and-a-half-inch-thick plank, the lower circular edge rabbeted out three-fourths of an inch by three-fourths of an

inch all round, so that it will just fit on the top of the cylinder and be held in place. In the center of the upper side of the platform I fasten a ring, to which a rope from the windlass can be attached, to lower or raise the platform when desired. The platform and ring are seen in place, *h h i*, Fig. 1. This platform may be used for the operator to stand upon, and also to deposit the cement, gravel, and small stones of which the grout wall is compounded.

To use my invention to the greatest advantage, a sufficient number of cylinders, like the one described, should be constructed to last a gang of workmen one day. In walling a well with grout, when the water from any cause cannot be removed, a curb or other foundation must be sunk, extending above the water. If the water can be removed, the operation may proceed directly from the bottom of the well. The cylinder is to be extended to full size, as seen at Fig. 1. It is then lowered by means of a windlass to the bottom of the well, plumbed and made steady, the platform lowered, and fixed in place on the top of the cylinder. The grout is next lowered and packed around the cylinder by the operator, who stands upon the platform, until it is filled to the top. The platform is then removed, another cylinder is lowered until it rests on the top of the first, the platform adjusted, and the work continued in the same manner for at least one day, or until the well is completed.

When the grout has set or hardened so as to stand without support, which it will do in one night, or a much shorter time if properly compounded, the cylinders are to be removed. To do this, the platform which has been used

on the last cylinder is to be removed, the extension-braces or stretchers are to be sprung upward by a pull on the ring at the upper end of the connecting-rod, opening the movable stave inward. The bail is attached to bail-loops, and by means of the before-mentioned windlass the cylinder is drawn out of the well. If the wall is yet incomplete the last cylinder should be raised only to the top of the grout, extended to its full size, then lowered until its lower end is a few inches below the top of the grout wall already filled in, care being taken that the cylinder stands plumb; then proceed as before until the grout wall is completed, which, when set and hardened, if rightly compounded, is as lasting and durable as if composed of one entire solid rock.

I make no claim to the use of a hollow cylinder in the process of walling wells, cisterns, and mine-shafts with grout; but

I claim as my invention—

1. A hollow cylinder supported by spring-steel ribs in the main part, which, in connection with movable or swing staves in place, forms a complete cylinder, the diameter of which can easily and evenly be reduced, and which is constructed and operated substantially as herein described and set forth.

2. The platform used on the top of the cylinder, supporting and aiding the operator in his work, constructed and operated substantially as hereinbefore described and set forth.

FREDERICK WILFORD.
